Primary Examiner—Doris Clark

[57] CLAIM

The ornamental design for a ladder mounted tool tray, as shown and described.

DESCRIPTION

FIG. 1 is a front elevational view of the ladder mounted tool tray showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The configuration of the extended tube is continuous throughout its length.
